UNITED STATES PATENT OFFICE

WILLIAM H. MILLSPAUGH, OF SANDUSKY, OHIO, ASSIGNOR TO THE PAPER & TEXTILE MACHINERY COMPANY, OF SANDUSKY, OHIO, A CORPORATION OF OHIO

PAPER-MAKING MACHINE

Application filed July 1, 1929. Serial No. 374,981.

This invention relates to paper making machines of the vacuum forming cylinder type, and aims to improve such machines with reference to the means for laterally confining the liquid stock on the forming cylinder.

Examples of vacuum forming cylinder machines are disclosed in my pending applications Serial Nos. 610,538, and 610,539, filed January 3, 1923, Ser. No. 29,600, filed May 10, 1925, and Ser. No. 123,757, filed July 20, 1926.

An illustrative embodiment of my present invention is shown in the accompanying drawings; only so much of the machine being shown as is necessary to illustrate the present improvement.

In said drawings—

Fig. 1 is a vertical section of a vacuum forming cylinder and cooperating vat to hold liquid stock.

Fig. 2 is an enlarged plan view of the vacuum forming cylinder and adjacent end of the vat.

Fig. 3 is an enlarged transverse section through the vat side walls near the cylinder and showing the cylinder in elevation; this view being taken on the vertical section line 3—3 of Fig. 1, looking in the direction of the arrow, and the figure being contracted for convenience of illustration by showing the vat side walls relatively close together and breaking away the intermediate portion of the cylinder and vat.

Referring to the drawings, 1 denotes the vacuum forming cylinder, which comprises a revolving suction roll having suitable suction box equipment in connection with pumping apparatus adapted for maintaining desired vacuum action against liquid stock supplied on the cylinder and for discharging the large amounts of water which are removed from the liquid stock in the process of vacuum-induced wet sheet formation. As shown, the suction roll consisting of a closely perforated metal shell contains a stationary suction box 2 bearing against the interior surface of the cylinder and cooperating therewith to provide the forming vacuum chamber 3 and a supplemental vacuum chamber 4. These chambers

connect with their respective pumping apparatus through the pipes 3^a and 4^a.

A porous medium covering the active portion of the vacuum forming cylinder is supplied in this instance by the endless apron 5 of fine wire cloth, hereinafter called the wire, which passes around and is driven by the rotating cylinder. The direction of rotation of the cylinder and travel of the wire is indicated by the arrow in Fig. 1. The wire in addition to supplying the surface upon which the wet paper sheet forms, serves also to carry off the sheet from the cylinder. The wire may deliver the sheet in contact with another similarly formed sheet on another wire for making plural ply paper, or it may deliver the sheet to a press felt in the manufacture of single ply paper.

The prepared liquid stock or pulp solution for forming the paper is supplied to or flows 70 against the cylindrical forming surface provided by the wire-covered portion of the cylinder, and is subjected to the action of suitable vacuum in the confronting vacuum chamber 3, inducing wet sheet formation as 75 explained in my applications aforesaid. As shown, the forming vacuum area established by the vacuum chamber 3 extends beyond or above the level of the contacting liquid body, so that the wet web or sheet emerges from the 80 liquid under continued exposure to the forming vacuum, thereby holding the formation intact and exerting a consolidating and moisture-reducing action on the emerging sheet. As the sheet passes over the succeeding vac- 85

uum chamber 4, it is subjected to further moisture-reducing action by the vacuum therein, which vacuum may be independently regulated to temper the moisture content as desired in case the sheet is to be bonded with 90 another sheet or sheets for formation of plural

ply paper.

An open-ended vat or holder 6 cooperates with the cylinder to hold the liquid stock, which is continuously supplied to the vat 95 from a source of supply and may by appropriate means be maintained at a desired level. The ends of the vat side walls adjacent to the cylinder are provided by the plates 7 having concave edges conforming to the curvature 100

of and closely overlying the wire or cylindrical forming surface of the cylinder but not in actual contact therewith. As stated in my aforesaid applications, the wet sheet will form with straight clean-cut edges if the liquid stock bearing on the cylinder be laterally confined between smooth-faced walls provided by such plates, leaving the slight crevices between the concave edges of the plates and the cylindrical forming surface open to the atmosphere. The sheet will form on the edges defined by said plates, i. e., immediately adjacent to the crevices between said plates and the cylindrical forming surface; the liquid being held from running out through said crevices by the outside atmospheric pressure, assisted by the damping effect of the layer of fibers gradually building up on the cylinder.

It will be seen that the plates 7 cooperate with the wire-covered portion of the cylinder to provide what may be termed stationary deckle surfaces. According to the present invention, these deckle surfaces are disposed in planes slightly oppositely oblique to planes at right angles to the axis of the cylinder so that the opposite deckle surfaces diverge slightly in the direction of the travel of the cylinder. In the particular construction shown, where the liquid stock bears on a lateral segment of the forming cylinder at its ascending side, the plates are slightly oppositely inclined to the vertical so that the plates are somewhat farther at the top than at the bottom, producing the divergence referred to. This will be apparent from Fig. 2, where it will be seen that the concave edges 8 of the plates diverge slightly from the bottom of the vat toward the top. The purpose and advantage of this arrangement is to relieve the edges of the sheet from frictional engagement with the plates, or to reduce such frictional engagement to a minimum. The vacuum-induced deposition of fibers to form the sheet is continuous as the cylindrical forming surface travels in contact with the liquid body past the vacuum chamber 3, so that the sheet is progressively built up on the forming surface. With the arrangement of the deckle surfaces described, the progressive building up of the edges of the sheet takes place at progressively receding surfaces, thus relieving the friction.

For clarity of illustration, the drawings somewhat exaggerate the divergence of the plates, which in practice may be very slight. For example, in a machine such as illustrated in the drawings having the plates 7 fifteen inches high, an inclination of each plate $\frac{1}{16}$ " to the vertical, producing a total divergence of $\frac{1}{8}$ ", is found sufficient. The divergence should not be too great lest the sheet should form with its edges tapering to a feather edge. Thus the plates while arranged to

provide the slight divergence described, are at the same time substantially or approximately vertical within the meaning of my aforesaid applications.

The plates 7 may be of metal or other suitable material. As in the case of the constructions disclosed in my aforesaid applications, the said plates are shown affixed as facing plates to laterally adjustable vat wall members 9. Said members have base flanges 10 bearing on extensions of the vat bottom and adjustably secured thereto by the slot and bolt connections 11; and lateral flanges 12 adjustably secured by the slot and bolt connections 13 to lateral vat wall extensions 14. This is to permit setting the deckle surfaces nearer together or farther apart, according to the width of sheet to be made; it being understood that the suction box chambers in the vacuum-forming cylinder have adjustable heads or ends for corresponding adjustment.

The numeral 15 in the drawings denotes a rubber strip which is fitted in the angle between the vat bottom and the cylinder to assist in preventing leakage of pulp liquid at that point.

It will be understood that the invention is not limited to the particular embodiment thereof herein shown and described.

What I claim as my invention, and desire to secure by Letters Patent, is:

1. A paper making machine having a vacuum forming cylinder and an open-ended vat cooperating therewith to hold liquid stock on the ascending side of the cylinder, the vat side walls adjacent the cylinder comprising plates oppositely inclined to the vertical so as to be further apart at the top than at the bottom, said plates having concave edges conforming to the curvature of and closely overlying the forming surface on the cylinder but not in actual contact therewith, which edges, by virtue of the inclination of said plates, diverge in the direction of rotation of the cylinder.

2. A paper making machine having a vacuum forming cylinder and an open-sided vat cooperating therewith to hold liquid stock, the vat side walls adjacent the cylinder comprising plates having concave edges conforming to the curvature of and closely overlying the forming surface on the cylinder but not in actual contact therewith and the said plates being arranged so that the said edges diverge in the direction of rotation of the cylinder.

3. A paper making machine having a vacuum forming cylinder and an open-ended vat cooperating therewith to hold liquid stock, the vat side walls having ends conforming to the curvature of and closely adjacent to the forming surface on the cylinder and the inner faces of said walls immediately adjacent to the cylindrical forming surface being in

planes oppositely oblique to a plane at right angles to the cylinder axis and diverging in the direction of rotation of the cylinder.

4. A paper making machine having a vacuum forming cylinder and means for laterally confining liquid stock thereon comprising stationary plates having concave edges conforming to the curvature of and closely adjacent to the forming surface of the cylinder, said plates arranged so that the said edges diverge in the direction of rotation of the cylinder.

5. A paper making machine having a vacuum forming cylinder and means for laterally confining liquid stock thereon comprising stationary plates having concave edges conforming to the curvature of and closely adjacent to the forming surface of the cylinder, the inner faces of said plates adjacent the said edges being in planes diverging in the direction of rotation of the cylinder.

6. A paper making machine having a vacuum forming cylinder and means for supplying liquid stock thereto and embodying stationary deckle surfaces diverging in the direction of rotation of the cylinder.

7. A paper making machine having a vacuum forming cylinder and cooperating laterally adjustable means providing stationary deckle surfaces, the said deckle surfaces diverging in the direction of rotation of the cylinder.

In witness whereof, I have signed my name to this specification.

35 WILLIAM H. MILLSPAUGH.
